Robert Everett,

Inventor:

Fritz Hermann Vagt.

By James L. Morris
Att'y.

UNITED STATES PATENT OFFICE.

FRITZ HERMANN VAGT, OF WANDSBECK, GERMANY.

DRIVING MECHANISM FOR CYCLES WITH ADJUSTABLE GEARING.

SPECIFICATION forming part of Letters Patent No. 611,210, dated September 20, 1898.

Application filed November 5, 1896. Serial No. 611,167. (No model.) Patented in England October 9, 1896, No. 22,410.

To all whom it may concern:

Be it known that I, FRITZ HERMANN VAGT, machine-constructor, of 11 Ahrensburger-strasse, Wandsbeck, near Hamburg, in the 5 German Empire, have invented a Driving 10 Mechanism for Cycles with Adjustable Gearing, (for which Letters Patent have been obtained in Great Britain, No. 22,410, dated October 9, 1896,) of which the following is a 15 specification, reference being had therein to the accompanying drawings.

This invention relates to apparatus whereby the proportion or ratio of the driven gear connected with the crank-shaft to the driven 15 gear connected with the hind or driving road-wheel of the cycle can be conveniently altered even while the cycle is being ridden.

In the accompanying drawings, Figure 1 is a side view of a bicycle with my invention applied thereto. Fig. 2 shows the apparatus detached from the machine and with the toothed driving-wheels out of gear. Fig. 3 is a view taken at right angles to Fig. 2; Fig. 4, a plan of the apparatus shown in Fig. 2. Fig. 5 25 shows the apparatus detached from the machine with the toothed driving-wheels in gear. Fig. 6 is a view of the apparatus shown in Fig. 2, but as seen from the other side. Figs. 2 to 6, inclusive, are drawn to a larger scale 30 than Fig. 1. Fig. 7 shows the apparatus as seen in Fig. 2, but drawn to a still larger scale. Fig. 8 is a sectional view taken through the center of Fig. 7. Fig. 9 is a view of the cover of the casing in which the wheelwork 35 is inclosed, and Fig. 10 is a section of Fig. 9.

The chief feature of this invention consists in the arrangement of the toothed wheel *a*, Figs. 5, 6, and 8, which can be moved into and out of gear with the toothed wheel *b*, fixed 40 on the crank-shaft, so that when these two wheels are geared together the machine is driven at a comparatively slow speed; but when they are out of gear the machine is driven at a quicker speed by the direct action 45 of the treadles.

Further features of the invention are the placing of the entire mechanism on the crank-shaft, the special devices for putting the toothed wheels into and out of gear, and a 50 special lever arrangement for effecting this putting in and out of gear of the wheels without requiring the rider to dismount.

The toothed wheel *b* on the crank-shaft is contained in a box or case *c*, Fig. 3, which has formed or secured therein the internally-toothed wheel *a*, Fig. 8, and which case is closed in front by a cover *d*, Figs. 9 and 10. The wheel *a* carries a crown-wheel *a'*, Figs. 7 and 8, over which the driving-chain runs. The cover *d* is formed with a circular opening in its center, through which passes the crank-shaft, the crank-arm *e* of which stands outside the case *c*, while the toothed wheel *b*, fixed on the crank-shaft, is contained within the case, Fig. 8. The back of the case *c* is 65 also formed with a central opening, in which is fitted a disk *f*, Figs. 2, 7, and 8, which is connected to the frame of the machine by means of a dovetail slide *g* and forms a fixed point around which the wheels *a* and *a'* can rotate. This disk *f* is provided with a radial slot *h*, through which the crank-shaft passes. The toothed wheel *a*, together with the chain-wheel *a'*, are carried on rollers, so that they 70 rotate on the disk *f* with the least possible friction. (See Figs. 7 and 8.) The whole case *c* and wheels *a* and *a'* can consequently turn round on the disk *f* when the wheel *a* is 75 put into gear with the wheel *b*, as seen in Fig. 5, so that the machine is driven at the slower 80 speed. When, however, the wheel *a* is put out of gear with the wheel *b*, a sliding bolt *k* on the crank-arm *e* takes into the notch *i* on the cover of the case, and the chain-wheel *a'*, and consequently the machine, is 85 driven by the direct action of the crank-arm *e* at a quicker speed. The cover of the case of course affords sufficient room for the play 90 of the toothed wheels contained in it, and it can be removed to allow of cleaning the interior at any time. On the back of this cover is a notch or recess *i*, into which a dovetail-shaped slide or bolt *k*, Fig. 3, on the crank-arm *e* can be pushed. This slide or bolt is subjected to the pressure of a spring *l*, which 95 presses it into the notch or recess *i*. A small pin *m* at the side prevents the slide *k* from being pressed too far in by the spring *l*. The slide *k* takes into the recess *i* when the two toothed wheels *a* and *b* are not in gear with 100 one another and their axes coincide; but it does not take into the recess *i* when the two toothed wheels *a* and *b* are geared together and their axes do not therefore coincide.

The required change of proportion of the gearing—that is to say, the change of power and speed—is thus brought about by simply putting the slide *k* into or out of gear with the recess *i*, which is effected by raising or lowering the case *c* and wheels *a a'* with reference to the crank-shaft.

The sliding part *g*, by which the disk *f* is connected to the frame of the machine, carries a bolt *n*, Figs. 3 and 4, which takes into a slot in the lever *o*, Figs. 2 to 5. This lever *o* is pivoted at one end to the rod *s* of the frame of the machine and is pin-jointed at its other end to a link-and-lever arrangement *p p'*, Figs. 1, 2, and 6, by means of which, as shown in Fig. 1, the whole mechanism can be put into or out of gear by the rider when mounted on the saddle by simply moving the handle *q* without the necessity of his dismounting.

It is evident that an increased leverage of crank is obtained when the wheels *a* and *b* are in gear with one another, because the axis of the crank-shaft does not then coincide with that of the chain-wheel and because the motion of the crank-shaft is then transmitted to the chain-wheel by reducing gearing, whereby power is gained and consequently an alteration of the speed is effected.

The whole apparatus must be so arranged with reference to the driving road-wheel and crank-shaft that the constant length of the driving-chain is not interfered with. This is, however, entirely a question of constructive detail.

What I claim, and desire to secure by Letters Patent of the United States, is—

1. In a driving-gear for cycles, the combination with a gear-wheel *b* fixed on the crank-shaft, of an adjustable casing *c* inclosing said gear-wheel and carrying an internal gear-wheel *a*, a sprocket-wheel *a'* on the periphery of the casing, a cover *d* on the casing having a recess *i*, means for adjusting the casing to throw said gear-wheels into and out of gear, 45 a bolt *k* transversely movable in the pedal-crank, and a spring *l* operating to force said bolt into the said recess when the gear-wheels are thrown out of gear, substantially as described. 50

2. In a driving-gear for cycles, the combination with a gear-wheel *b* fixed on the crank-shaft of a centrally-apertured, adjustable casing *c* inclosing said gear-wheel and carrying an internal gear-wheel *a*, a sprocket-wheel *a'* 55 on the periphery of the casing, a slotted link *n* pivoted to the cycle-frame, a sliding support *g* pivotally connected to said link and carrying a disk *f* disposed in the central aperture in the casing, antifriction-rollers *r* 60 journaled in bearings on the casing and having a rolling bearing on the periphery of the disk, a lever connected with the link *n* for raising and lowering the casing to throw the gear-wheels into and out of gear, and means 65 for automatically locking the pedal-crank and casing together when the gear-wheels are thrown out of gear, substantially as described.

In witness whereof I have hereunto set my hand in presence of two witnesses.

FRITZ HERMANN VAGT.
